UNITED STATES PATENT OFFICE.

CARL HORIX, OF CHICAGO, ILLINOIS.

COMBINATION TOOL.

Original application filed April 15, 1926, Serial No. 102,101. Divided and this application filed December 30, 1926. Serial No. 157,895.

The present application is a division of my application Serial No. 102,101, filed April 15, 1926, for novelty combination tool. In said application the claims are drawn to 5 the construction of the cutting tool and its cooperation with the openings in the handle portion. These features are shown and described herein but not claimed.

This invention relates to a pocket tool 10 comprising a plurality of implements mounted on a single handle, and has for one of its objects the provision of such a tool which shall efficiently perform the various functions for which it is designed and 15 in which the various implements will be effectively encased when not in use so that the tool may be carried in a pocket without danger of tearing the lining of the pocket, and so that each implement may be readily 20 and conveniently brought into operation when desired.

A further object is to provide a tool of the nature referred to which shall be novel and attractive in appearance, economical 25 to manufacture, and strong and efficient in use.

Other objects of the invention will appear from the following description.

The invention is exemplified in the combination and arrangement of parts shown 30 in the accompanying drawing and described in the following specification, and it is more particularly pointed out in the appended claims.

35 In the drawing—

Fig. 1 is a side elevation of the combination tool with the various implements closed;

40 Fig. 2 is an end elevation looking from the right in Fig. 1;

Fig. 3 is a top plan view of the tool;

Fig. 4 is a section on line 4—4 of Fig. 1;

Fig. 5 is a side elevation of the tool with the knife blade open;

45 Fig. 6 is a section on line 6—6 of Fig. 5; and

Figs. 7 and 8 are plan and elevation, respectively, of a modification.

The tool comprises a handle member 10 50 including plates 11 and 12 secured together by rivets 13 and 14. The plates 11 and 12 are stamped to provide inwardly offset portions at the ends secured together by the rivet 13 and along the edge shown at the

top of Fig. 2. These offset portions bear 55 directly against each other to hold the main body of the plates in spaced relation from each other, thus providing a recess between the plates to receive the blade holder pivotally mounted on the rivet 14. The blade 60 holder comprises a pair of comparatively thin plates 15 and 16 pivotally supported by the rivet 14 and arranged at opposite sides of a spacing washer 17 surrounding the rivet 14, as shown in Fig. 4. The plates 65 15 and 16 are independently movable upon the pivot 14, but the plate 16 is provided with a flange 18 at one edge to limit the movement of the plate 15 in one direction. Both plates are provided with stop shoulders 70 19 for engaging a stop 20 formed by a lug bent inwardly from the side plate 11 and forming a spacer for the two side plates. The stop members 19 and 20 limit the outward movement of the blade holder to hold 75 the blade holder in alignment with the handle as shown in Fig. 5.

The plate 16 has spaced projections 21 struck inwardly to engage spaced openings in a thin blade 22 such as is used for safety 80 razors. In placing the blade in position over the lugs 21, the plate 15 is swung out of registration with the plate 16 exposing the inner face of the plate 16. The blade 22 is then placed in position and the plate 15 rotated to engage the flange 18 so as to cover the blade 22 and hold it in place. The plate 16 is provided with an overhanging flange 23 which engages the outer end of the plate 15 to hold it tightly against the face of the 90 blade 22.

The plate 15 is provided with outwardly struck portions 24 providing arcuate grooves on the inner face of the plate. This provides clearance for the lugs 95 21 when the plate 15 is rotated relative to the plate 16. The outermost projection 24 is preferably knurled or roughened to facilitate swinging the plate 15 relative to the plate 16. The lugs 21 are located a sufficient 100 distance from the flange 18 so that the inner edge of the blade 22 will be spaced from the inner face of the flange, thus protecting the edge against being dulled by engagement with the flange 18. The plates 15 and 16 105 are cut away, as shown at 25, to expose the outer edge of the blade 22 when the holder is open. The cut-away portion 25 termi-

nates at a short distance from the inner end of the blade holder to provide a stop shoulder 26 which prevents the edge of the blade from engaging the inner edge of the recess in the handle when the blade holder is closed.

The handle plates 11 and 12 are provided with registering perforations 27 so that the device may be used as a cigar cutter. In 10 severing the end of a cigar, the blade is opened a sufficient distance to clear the perforations 27 and the end of the cigar is inserted through these perforations. When the blade is closed the inserted end will be 15 severed.

The plate 16 may be provided with a pointed projection 28 which can be used as a nail cleaner or for any other purpose which such a pointed projection will serve.

20 A notch 29 is formed in the ends of the handle plates and the edges of the notch are beveled to form cutting edges. This notch is convenient for severing cords or strings, such as are used in tying packages.

25 At the opposite side of the handle plates from the notch 29 there is provided a spur 30 which co-operates with a fulcrum 31 to form a bottle cap remover.

The plates 11 and 12 are formed outwardly at 32 to provide a recess in which a cork-screw 33 is pivoted on a pivot pin 34. The opposite end of the cork-screw is received between ears 35 formed on the edges of the plates 11 and 12. These ears are curved to 35 conform to the radius of the cork-screw and the upper ends of the ears project beyond the center line of the cork-screw so that they are bent inwardly a sufficient amount to retain the cork-screw in folded position 40 against the edge of the handle plates. The cork-screw when closed in this position forms, together with the ears 35, what is in effect a circular bead or enlargement along the edge of the handle members so that a 45 better grip can be secured on the handle for operating the blade 22 as a knife. The ears 35 and supporting portions of the plates 11 and 12 are sufficiently resilient to hold the cork-screw in folded position, thus guarding 50 the pointed end of the cork-screw and preventing the screw from opening in the pocket. If sufficient force is exerted the cork-screw may be opened to a position at right angles to the handle member so that 55 it may be used for removing bottle stoppers. When the cork-screw is again closed the arcuate shape of the screw will produce a wedging action between the ears 35 which springs them apart sufficiently to permit the 60 screw to snap into place between the ears.

It will be seen from the drawing and description that the arrangement provides a tool in which the various implements are conveniently and effectively placed so that 65 the parts fold into compact relation, making

the device neat in appearance and convenient to carry in the pocket. The device embodies in one tool, implements for performing a large number of recurring operations so that the tool is exceedingly convenient 70 and useful.

In the modified form of the invention shown in Figs. 7 and 8, the retainer plate 36 for the blade 22 instead of being hinged on the pivot 14, is entirely removable and 75 slides beneath the flange 23 and a co-operating flange 37 struck up from the plate 16. The plate 36 is formed outwardly in straight parallel raised portions 38 leaving grooves on the under side of the plate for blade 80 holding lugs.

I claim:—

1. A tool comprising a pair of handle plates disposed face to face, a cork-screw pivotally mounted between said handle 85 plates, said plates having outwardly curved ears forming a recess in position to receive a portion of the free end of said cork-screw when said cork-screw is folded against the edge of said plates, the extremities of said 90 ears being curved inwardly and extending beyond the axial line of said cork-screw when said cork-screw is disposed in said recess so that the ends of said ears will spring inwardly past the portion of said 95 cork-screw having maximum width to retain said cork-screw in said recess and to form a guard for the pointed end thereof.

2. A tool comprising a pair of handle plates secured together face to face, said 100 handle plates having portions thereof spaced apart at one edge of said plates and intermediate the ends of said plates, a cork-screw pivotally mounted in the recess between the spaced portions of said plates, the edges of 105 said plates having an elongated notch therein at one side of said recess so that a portion of said cork-screw will be exposed when folded against the edges of said plates, the portions of said plates at the end of said notch 110 opposite said recess being curved to form an arcuate recess, the sides of which extend outwardly from the edges of said plates a distance somewhat greater than the radius of 115 said cork-screw while the extremities of said portions are curved inwardly leaving a space between the extremities somewhat less than the maximum diameter of said cork-screw so that when said cork-screw is closed against said extremities the sides of said recess will be sprung outwardly to permit said cork-screw to enter said recess and will be 120 snapped together by the resiliency of said plates to retain said cork-screw in folded position with the end of said corkscrew disposed in said recess.

3. A tool comprising a pair of handle plates secured together face to face, a cork-screw pivotally mounted on said handle plates at one edge thereof and between the 125

ends of said plates, retaining ears formed on said plates for receiving the free end of said cork-screw when folded against the edge of said plates, and means for holding said plates together at a point spaced from the edge thereof upon which said ears are mounted so that the resiliency of said plates will permit said ears to spring outwardly to receive the end of said cork-screw.

In testimony whereof I have signed my name to this specification on this 24th day of December, A. D. 1926.

CARL HORIX.
